US00D608006S

(12) **United States Design Patent**
Avitable et al.

(10) **Patent No.:** **US D608,006 S**
(45) **Date of Patent:** **** Jan. 12, 2010**

(54) **COMPRESSION DEVICE**

(75) Inventors: **Raymond C. Avitable**, Framingham, MA (US); **Richard P. Rego, Jr.**, Mansfield, MA (US); **Jennie Brown**, Providence, RI (US); **Malcolm C. Bock**, Medfield, MA (US)

(73) Assignee: **Tyco Healthcare Group LP**, Mansfield, MA (US)

(**) Term: **14 Years**

(21) Appl. No.: **29/325,934**

(22) Filed: **Oct. 8, 2008**

(57) **CLAIM**

The ornamental design for a compression device, as shown and described.

DESCRIPTION

FIG. 1 is a perspective view of a compression device;

FIG. 2 is a front elevational view thereof; and,

FIG. 3 is a rear elevational view thereof.

It is understood that the compression device shows no appreciable thickness.
